UNITED STATES PATENT OFFICE.

MILTON MURRAY, OF WILLIAMS WHARF, VIRGINIA.

NON-REFILLABLE BOTTLE.

1,102,349.

Specification of Letters Patent.

Patented July 7, 1914.

Application filed May 1, 1913. Serial No. 764,850.

To all whom it may concern:

Be it known that I, MILTON MURRAY, a citizen of the United States, residing at Williams Wharf, in the county of Mathews and State of Virginia, have invented certain new and useful Improvements in Non-Refillable Bottles, of which the following is a specification, reference being had therein to the accompanying drawing.

10 This invention relates to non-refillable bottles and has for its object the production of a simple and efficient valve means which may be applied to the neck of the bottle so as to prevent the bottle from being refilled after once being emptied.

Another object of this invention is the production of a simple and efficient means for holding the valve within the neck of the bottle and preventing the removal without breaking the neck of the bottle.

With these and other objects in view, this invention consists of certain novel constructions, combinations and arrangements of parts, as will be hereinafter fully described and claimed.

In the drawings:—Figure 1 is a central vertical section through the bottle and valve. Fig. 2 is a sectional perspective view of the bottle, showing the valve casing positioned therein. Fig. 3 is a section taken on line 3—3 of Fig. 1. Fig. 4 is a detail perspective of a modified form of the valve casing which may be used in connection with the present invention.

35 By referring to the drawings, it will be seen that 1 designates the body of the bottle which is provided with a neck 2 which neck is of the usual shape having a circumferential bead portion 3 formed upon the outer face thereof. A socket or groove 4 is formed upon the inside of the neck 2 in alinement with the bead portion 3 and this socket portion constitutes a circumferential channel in which the locking washer 5 is placed 40 for retaining the valve casing hereinafter described within the neck of the bottle.

The valve casing 6 comprises a substantially tubular body portion having a rounded tapering end 7 which is provided with a 50 compartment 8 in which the ball valve 9 works. A discharge aperture 10 is formed in the bottom of the tapering end 7 of the casing 6, and the ball valve 9 normally rests in this socket for preventing the flow of liquid into the body. The valve casing 6 is provided with a central discharge aper-

ture 11 and a shield housing 12 is carried by the casing both above and below the aperture, as illustrated clearly in Figs. 1 and 2, which shield casing 12 is supported by means of the legs 13 which space the shield housing 12 from the face of the casing 6 to allow the liquid to pass out through the aperture 11 when the bottle is inverted and the ball valve 9 is removed from the aperture 10. It will be seen that this shield housing 12 upon the top of the casing 6 will prevent the insertion of articles in the casing 6 to attract the ball valve 9 and remove the same from the seat 10. The housing 12 upon the bottom of the casing 6 is so formed as to prevent the ball from closing the aperture 11 when the bottle is inverted. It, of course, should be understood that the lower tapering end of the casing 6 is blown upon the body of the valve 6 in the usual manner in order that the ball valve 9 may be placed therein and in order that the housing 12 may be formed upon the lower end of the casing 6 prior to 70 integrally connecting the tapering end 7 to the body of the casing 6.

The casing 6 is provided with a circumferential channel 14 which channel is adapted to register with the channel or groove 4 formed in the neck of the bottle 2. The corrugated spring washer 5 is carried by the channel 14 of the casing 6 and is slit as indicated at 16 in Fig. 3 so as to allow the washer to expand and contract to facilitate the placing of the casing 6 within the neck of the bottle. It should be understood that as the casing 6 is placed in the bottom the corrugated washer 5 will contract so as to be entirely shielded within the channel 14, 95 but as soon as the channel 14 registers with the channel 4 in the neck of the bottle, the corrugated washer 5, which is formed of spring metal, will expand so as to have the corrugations 17 alternately engage the channel 14 of the casing 6 and the channel 4 of the neck of the bottle. By means of the efficient securing means, it will be seen that a very durable device has been produced for holding the valve casing within the neck of the bottle and at the same time holding the valve casing in such a manner as to prevent the casing from being removed without breaking or injuring the bottle.

As is illustrated in Fig. 4, the protector 110 housing 18 may be placed above the casing 19 and the supporting legs 20 are formed

so as to extend flush with the sides of the casing 19 and support the protector housing 18 above the discharge aperture 21. This structure is especially used where 5 a large discharge opening is desired and to accommodate this large opening the legs 20 are formed so as to extend parallel with the sides of the casing. It should be understood that the lower tapering end 10 22, like the structure illustrated in Figs. 1, 2 and 3, will be formed substantially integral to the casing 6 owing to the fact that the same will be blown with the casing and thereby constitute a substantially one-piece 15 structure, the parts of which may not be separated from each other.

It, of course, should be understood that when the bottle is in a vertical position, the ball valve 9 will fit upon the seat 10 and 20 prevent the passage of liquid into the bottle. On the other hand, if the bottle should be inverted for the purpose of filling under pressure, the pressure passing through the valve casing will force the valve ball 9 into 25 engagement with the valve seat and thereby prevent the passage of liquid into the body of the bottle. It, of course, should be understood that the ball 9 may be formed of suitable material to accomplish the desired purpose. 30

Having thus described the invention, what is claimed as new, is:—

A non-refillable bottle comprising a neck, said neck provided with an outstanding circumferential portion formed integral therewith, a casing positioned within said neck and comprising a substantially inverted conical shape body, said body provided with a discharge opening at one end, said body also provided with a centrally located longitudinally extending aperture, a shield extending over each end of said aperture, legs supporting said shield in spaced relation from the ends of said aperture and constituting means for preventing the passage of an instrument through said body, a spring washer, said body provided with a notch formed upon the sides thereof, said spring washer provided with inwardly extending portions fitting in said notches of said body, said neck provided with a notch portion, and outstanding portions of said spring washer also fitting in said notch of said neck for holding said body within said neck. 35 40 45

In testimony whereof I hereunto affix my 50 signature in presence of two witnesses.

MILTON MURRAY.
